(57) **CLAIM**

The ornamental design for a wheel, as shown and described.

DESCRIPTION

FIG. 1 is a left front perspective view of a wheel according to the invention.

FIG. 2 is a front view of the wheel shown in FIG. 1; and, FIG. 3 is a right side view of the wheel shown in FIG. 1, the left side view being a mirror image thereof.

The broken line showing of the rim of the wheel, the valve stem hole, the bolt holes and the center hole is included for the purpose of illustrating environment and forms no part of the claimed invention.

1 Claim, 2 Drawing SheetsFIG. 1

FIG. 2

FIG. 3
